UNITED STATES PATENT OFFICE.

JOHN W. HULL, OF SAN ANTONIO, TEXAS, ASSIGNOR OF ONE-FOURTH TO HENRY D. MANTON, OF SAN ANTONIO, TEXAS.

WALL-BLOCK.

1,398,695.

Specification of Letters Patent. Patented Nov. 29, 1921.

Application filed July 12, 1920. Serial No. 395,438.

To all whom it may concern:

Be it known that I, JOHN W. HULL, citizen of the United States, residing at San Antonio, in the county of Bexar and State 5 of Texas, have invented certain new and useful Improvements in Wall-Blocks, of which the following is a specification.

This invention relates to improvements in masonry and concrete structures and more 10 particularly to wall blocks.

An important object of this invention is to provide a building block or tile having novel means whereby the same may be securely connected to the adjacent blocks so 15 that a wall made from a plurality of the blocks will not be likely to crack as the result of settling of the foundation.

A further object of the invention is to provide a building block having a T-shaped recess in its upper face adapted for the reception of a T-shaped locking lug on the adjacent block, the said T-shaped locking lug being adapted to be confined within said 20 T-shaped recess by mortar or the like.

The invention forming the subject matter 25 of this application aims also to provide a building block which is of highly simplified construction, durable in use, and cheap to manufacture.

Other objects and advantages of the invention will be apparent during the course 30 of the following description.

In the accompanying drawing, forming a part of this application and in which like 35 numerals are employed to designate like parts throughout the same:

Figure 1 is a fragmentary perspective of one course of a wall composed of a plurality of the improved blocks.

Fig. 2 is a group perspective of a plurality of the improved blocks.

Fig. 3 is a vertical transverse section taken on line 3—3 of Fig. 2.

In the drawing, wherein for the purpose 45 of illustration is shown a preferred embodiment of the invention, the numeral 5 generally designates one course of a wall composed of a plurality of blocks forming the subject matter of this application.

The invention forming the subject matter 50 of this application embodies a block 6 which is preferably hollow and is provided with longitudinal ribs 8 intersected by a horizontally arranged longitudinally extending re-

that any suitable arrangement of reinforcing ribs may be employed to strengthen the blocks. The block 6 is provided at one end with a T-shaped locking lug 12 which is adapted to be received within a T-shaped recess 14 in the upper face of the adjacent end of the adjacent block. The shank 16 of the T-shaped locking lug is adapted to be received within a longitudinally extending passage 18 of the T-shaped recess and serves 60 as a means for preventing the lateral movement of one of the blocks with relation to the other blocks. When set up in courses, the head of each of the T-shaped lugs 12 serves to securely connect the several lugs 70 and thereby prevent cracking of the wall due to the settling of the foundation.

The end blocks of the wall may be provided with T-shaped recesses 26 adapted for the reception of the T-shaped locking lugs 75 12 of the adjacent blocks. As illustrated in Fig. 2, the passage 28 which receives the shank 16 of the T-shaped lug 12 extends transversely of the block and opens out 80 through one side of the same.

It will be noted with reference to Fig. 1, that the upper faces of the lugs 12 are flush with the surfaces of the adjacent slots and, therefore, there are no objectionable projections to interfere with laying additional 85 courses of blocks when building a wall.

With reference to the foregoing description taken in connection with the accompanying drawings, it will be observed that a building block constructed in accordance 90 with this invention may be manufactured at an extremely low cost and when used in wall construction will prevent the wall from unnecessarily cracking due to settling of the foundation.

It is to be understood that the form of the invention herewith shown and described is to be taken as a preferred example of the same and that such minor changes in arrangement and construction of parts may 100 be made as will remain within the spirit of the invention and the scope of what is claimed.

Having thus described the invention, what is claimed as new is:

1. A building block comprising a hollow body adapted to be arranged horizontally with similar bodies in forming courses and provided on its upper face with lugs forming a T-shaped recess at one end portion, 110

said **T**-shaped recess including a longitudinal passage opening through one end between the sides of the body, and a transverse passage opening through opposite sides of the body, the opposite end of said body being provided with a **T**-shaped recess having a transverse passage opening through the end and one side of the body and a longitudinal passage opening through the opposite side of the body.

2. The combination of building blocks ar-

ranged horizontally in courses and each provided on its upper face with lugs defining a **T**-shaped recess opening through one end and the sides of the block, the adjacent block 15 being provided at one end with a **T**-shaped projection to fit within said **T**-shaped recess with its several faces flush with the corresponding faces of the lug defining the recess.

In testimony whereof I affix my signature.

JOHN W. HULL. [L.S.]
